UNITED STATES PATENT OFFICE.

HERBERT V. BIGHAM, OF ROARING SPRINGS, TEXAS.

DESIGN FOR A FLOWER STAND.

Application filed February 19, 1923. Serial No. 5,209. Term of patent 3½ years.

To all whom it may concern:

Be it known that I, HERBERT V. BIGHAM, a citizen of the United States, residing at Roaring Springs, in the county of Motley and State of Texas, have invented a new, original, and ornamental Design for a Flower Stand, of which the following is a specification, reference being had to the accompanying drawing, forming part thereof.

The figure is a perspective view of a flower stand embodying my invention.

I claim:

The ornamental design for a flower stand as shown:

HERBERT V. BIGHAM.
